Arthur M. Hood.
ATTORNEY

UNITED STATES PATENT OFFICE.

JAMES H. JOHNSON, OF INDIANAPOLIS, INDIANA, ASSIGNOR TO UNITED STATES HOFFMAN MACHINERY CORPORATION, OF NEW YORK, N. Y., A CORPORATION OF DELAWARE.

HAT BLOCK.

Application filed October 31, 1922. Serial No. 598,186.

To all whom it may concern:

Be it known that I, JAMES H. JOHNSON, a citizen of the United States, residing at Indianapolis, in the county of Marion and State of Indiana, have invented new and useful Hat Blocks, of which the following is a specification.

My invention relates to improvements in hat blocks and has for one of its objects the provision of means whereby blocks of various sizes and shapes may be suitably heated for blocking and shaping hats, from a single heating apparatus.

For the purpose of disclosing my invention I have illustrated certain embodiments thereof in the accompanying drawings in which:

Fig. 1 is a side elevation of an apparatus embodying my invention.

Fig. 2 is an enlarged detail section thereof and

Fig. 3 is an elevation of a modified form of block.

In the structure illustrated I provide a suitable base 1 which is preferably cylindrical in shape and at its bottom is provided with chamber 2 and near its top with a socket 3, the socket 3, preferably being an enlargement of the chamber 2 whereby a shoulder 4 is formed on the inner circumference of the base. This base is preferably mounted upon a bench 5, or other supporting member, which bench is recessed at 6 to receive the lower end of the base, a flange 7 being provided for supporting the base in position on the bench. This flange 7 is preferably screw threaded on to base 1 and held on bench by means of screws or bolts or the like, whereby when desired, the base may readily be removed from the bench.

The hat forming block 8 is rotatably mounted on the base and this block comprises a hollow shell preferably formed of aluminum and having a plurality of steam openings 9 formed therein. The bottom of the shell is provided with interiorly extending annular flange 10 by which it is secured to a disc-like extension 11 of a swivel neck 12 arranged to be inserted in the socket 3 of the base. The neck 12 is

hollow so that there will be a communication through this neck between the chamber 2 and the interior of the block shell 8. Screw threaded into the bottom of the base 1 is a steam supply pipe 13 provided with a suitable hand valve 14 and this pipe communicates with a jet head 15 arranged within the chamber 2 and provided with a plurality of jet openings 16. By the use of the head the projection of any water of condensation upwardly through the neck is prevented, a point of advantage as it is not desirable to have water pass through the steam openings 9. A drain port 17 is formed in the bottom of the chamber 2 which port communicates with a drain pipe 18 having a suitable cock 19 at its end.

In operation the shell 8 of suitable size and shape for the hat to be blocked is selected and the neck 12 thereof is socketed into the base 1, whereby when live steam is admitted through the jet 15 it will pass out through the openings 9 into the hat, heating the same and softening the hat so that it may be suitably blocked. At the same time the joint between the block and base 1 permits the block to be freely rotated so that the operator may properly manipulate the hat in blocking the same.

In Fig. 3 I have illustrated another form of block which is particularly adapted for hats of the "fedora" type. The shell of this block it will be noted, is provided with a center crease or recess 20 to permit the blocking of the crease in a hat of this character.

I claim as my invention:

1. In a device of the character specified, the combination of a socketed base; means for introducing steam into the lower portion thereof; means serving to prevent water of condensation from passing upwardly through the base; a hollow perforate hat forming block presenting an exterior surface of a conformation of the hat to be blocked, such surface being free of any projections which preclude the drawing of the hat directly against the same; and a hollow neck piece extending from the base of the block and fitting closely within the socketed base.

2. In a device of the character specified, a hollow perforated hat forming block secured to the neck.
the combination of a socketed base; a steam supply pipe connected therewith; a jet chamber located within the lower portion of the
5 base and communicating with the steam supply; a swivel neck seated within and supported by the upper end of the base; and

In witness whereof, I have hereunto set my hand at Indianapolis, Indiana, August, A. D. one thousand nine hundred and twenty two.

JAMES H. JOHNSON.
